UNITED STATES PATENT OFFICE

OSCAR A. ROSS, OF NEW YORK, N. Y., ASSIGNOR TO GENERAL RAILWAY SIGNAL COMPANY, OF ROCHESTER, NEW YORK

ALTERNATING-CURRENT RELAY

Application filed November 14, 1925. Serial No. 69,130.

This invention relates to relays, and more particularly to that class of relays known as signalling relays employing alternating current for their operation.

5 One object of my invention is to furnish a relay having a very low resistance component in the local winding, in this manner producing a low power factor thereby producing a large phase displacement between the windings of what is known as a "track" relay further resulting in a high torque the net result being a highly efficient operating device.

Another object is to furnish a relay having a high "drop-away" percentage, said "drop-away" being the ratio of energy required to make full contact, to the energy reduced to the point where said relay will open its contacts fully. I accomplish this by operating the relay rotor in a vertical plane and stepping said rotor on a bearing of very hard substance whereby the friction of the bearings are reduced to a minimum, and in addition by employing a novel form of contact disclosed in my co-pending application for Letters Patent Serial Number 65,399, filed Oct. 28th, 1925.

Another object is to furnish a relay in which all stationary and adjacent movable parts between which a substantially small air gap exists, will have said air gap arranged in a vertical plane, whereby, if any dirt or foreign matter enters therein, it will fall through said air gap and not cause interference with said movable parts. In relays having rotors operating in a horizontal plane the air gap must likewise be in a horizontal plane. If for any reason sufficient dirt, compound, or foreign matter accumulates in said air-gap it may stick said relay in the clear position, a grave offense in the signalling art. Such accumulation of foreign matter may occur from overheating of the relay windings from any cause, as for example a charge of lightning.

Another object is to produce a relay in which, although the rotor is safe guarded from sticking due to accumulation of foreign matter in the air-gap, its operation will be visible to maintainers, or inspectors. Whereas it is true that a rotor will stick if

conditions warrant, and that visibility of the rotor does not, in itself, prevent such sticking, there is a great deal of satisfaction and safety due to timely warning, in watching, or being able to see all movable parts in operation.

Another object is to provide means for automatically heating the interior of a relay during periods of extremely cold weather when lowered temperatures might cause interference with the proper operation of said relay.

Another object is to furnish a relay wherein the various parts are so arranged that, whereas the operation of the rotor is visible, the windings producing the energy, or rather torque for operating said rotor, are completely enclosed and invisible to an on-looker, in this manner making a neat appearing device as most windings employed in similar devices are unsightly.

Other objects and advantages will appear as the description of the invention progresses, and the novel features of the invention will be pointed out in the appended claims.

This invention consists in the novel construction and arrangement of parts herein-after described, delineated in the accompanying drawings, and particularly pointed out in that portion of the instrument wherein patentable novelty is claimed for certain and peculiar features of the device, it being understood that, within the scope of what herein-after thus is claimed, divers changes in the form, proportions size and minor details of the structure may be made without departing from the spirit of the invention, or sacrificing any of the details.

In describing the invention in detail, reference is had to the accompanying drawings, wherein I have illustrated one embodiment of my invention and wherein like characters of reference designate corresponding parts throughout the several views, and in which:

Fig. 1, is an elevational front view of the preferred form of my invention;

Fig. 2, is a top view, with what is known as the contacting mechanism removed to show the interior of the relay;

Fig. 3, is a part sectional, part elevational view taken on the line A—A of Fig. 1;

Fig. 4, is an enlarged view of part of the contracting mechanism;

Fig. 5, is a top view of the same taken on line B—B of Fig. 4;

Fig. 6, is a diagrammatic view of the winding on the stator illustrating how a minimum amount of wire is obtained;

Fig. 7, is also a diagrammatic view of well known forms of stators illustrating the reason for employing a relatively large quantity of wire on said stators;

Fig. 8, is a vector diagram showing substantially the relative phase relations of the windings on the stator shown in Figs. 7 and 8;

Fig. 9, is a modified form of the mechanism as adapted to a three-position relay;

Fig. 10, is a part sectional, part elevational side view of the same mechanism taken on line C—C, of Fig. 9;

Fig. 11, is a top view of the same mechanism taken on line D—D of Fig. 9;

Fig. 12, is an enlarged detail of one of the counter-weight stops; and

Fig. 13, shows diagrammatically, heating means for the relay.

Referring to Figs. 1, 2, 3, 4, 5 and 6, relay 1 comprises two general units, one the contacting mechanism 2, and the other the motor movement and case 3.

Contacting mechanism 2, comprises insulation plate 4, secured by screws 41 and depending from which are bearing brackets 5 and 6, pivotally mounted in which is contact bar 7, having trunnions 8 and 9, at each end and circuit closing devices, or contacts as 10 and 11 mounted on opposite parallel sides thereof. Said contacting devices 10 and 11, are more fully described in my co-pending application for Letters Patent Serial Number 65,399, filed Oct. 28, 1925, pliable material pieces 12 and 13, plate 14 and screws 15—15 serving to hold said contacts to said bar. Also secured to bar 7, by screws 38—38 is arm 37, carrying counter weight 39 adjustably secured by screw 40. Circuit controlling device 10 is generally known as a front contact and its terminals are connected to the rear binding posts 16 and 17, by metal extensions 18 and 19, and flexible conductors 20 and 21, passing through insulated guide strip 22. Circuit controlling device 11, is generally known as the back contact and its terminals are connected to front binding posts 23 and 24 through metal extensions 25 and 26, and cables 27 and 28, also passing through guide strip 22. Binding posts 29—29 are four in number and form the terminals for the windings on the stators of the relay motor, conductors 32, 33, 35 and 36 connecting to said posts. Binding posts 30, form the terminals for thermostat 31, of any well known construction and the terminals of which are placed in the circuit of one of the stator windings, preferably the phase hav-

ing the lower inductance, as for example the track phase of a track relay. Also attached to contact bar 7, by screws 42—42, is lever 43, said lever being the division point between aforesaid contact unit 2, and motor unit.

Motor unit 3, comprises molded metal frame, or case 44, the four vertical sides of which are enclosed by doors 45, 46, 47 and 48, secured by screws 49—49 and contain transparent sheets 50—50, preferably of glass set in said doors with plastic cement and are held in place by the clamping effect of screws 49—49, a pliable gasket 51—51, serving to prevent dust or other foreign matter from entering the relay interior.

Case 44, has a centrally disposed machined projection 52, mounted on which is stator 53 comprising lamina 54, insulated washers 55—55, secured by nut 56, and in the slots 57—57 of which are wire wound coils 58a, 58b, 58c, 58d and 59a, 59b, 59c, 59d, forming windings of a split phase relay, and for purpose of illustration are shown in Fig. 6, as a local and track winding of a track relay, a device well known in the art.

Also forming part of case 44, are machined lugs, or projections 60—60, rigidly secured in which are studs 61—61 acting to locate stator 62, preferably termed a core, with respect to stator 53, nuts 65—65 securing said core in place. Core 62, comprises lamina 63 and 64, brackets 66, containing bearing 67 adapted to guide the upper end of shaft 69 being clamped between said stator, or core 62 and nuts 65.

Rotor 68, comprises shaft 69, to which is rigidly secured flanged support 70, carrying metal rotor shell 71, secured by rivets 72—72, and has the lower end of shaft 69 stepped in bearing 73, more fully described in my co-pending application Serial Number 65,398, filed Oct. 28th, 1925, the upper end being guided by bearing 67, the protruding portion carrying lever 74, the outer end of which, is limited by stops 74a and 74b secured to stator, or core 62, and is pivotally connected to link 77 by screw 76, said link being also pivotally connected to lever 43 by screw 43a. Pin 75 serves to secure lever 74 to shaft 69.

Incandescent lamps 78 and 79 adequately secured in case 44, and receiving energy from the source supplying the relay windings, are controlled by manually operated switch 80 for inspection purposes, and by thermostat 116, said thermostat acting to cut in said lamps upon a predetermined lowering of temperature within the case 44, said lamps thereafter acting to increase the temperature within said case.

Figs. 9, 10, 11 and 12, represent certain operating parts for a three position relay of normal operating speed, and in which, sleeve 81, rigidly secured to shaft 69, supports frictionally mounted pinion 82 meshing with

gear sector 83, rigidly mounted on shaft 84, the lower end of which is stepped in bearing 85, adjustably secured in case 44, and the upper end guided by bearing 86 likewise adjustably secured in case 44. After adjustment of said bearings to align sector 83 with pinion 82, both of said bearings are sealed in place.

Screw 87, secured to sector 83, pivotally actuates links 88 and 89 adapted to raise counter weights 90 and 91, by their movement in one direction only, slots 92 and 93 serving to give free movement in the opposite direction. Counter weights 90 and 91, are pivotally mounted on pins 94 and 95 rigidly secured to bracket member 96, and have arms 97 and 98 containing screws 99 and 100 co-acting with the slotted ends of links 88 and 89, said counter weights normally resting on stops 101 and 102.

Said bracket 96, is secured to studs 61—61 by nuts 65—65 and has extensions 103 and 104, containing adjustably secured screws 105 and 106 fitted with resilient stops 107, nuts 108—108 serving to lock said screws in place.

Sector 83 also has arm 109 containing screw 110, pivotally controlling one end of link 111, the other end of which is pivotally secured to lever 112, by screw 113, attached to a contact bar, as 7, by pins 114.

Referring to Figs. 6 and 7, the dimensions E, and F, illustrate substantially the relative lengths of wires between slots in a four pole sixteen slot stator, stator 115 (Fig. 7) representing the usual form of wound outer stator, and stator 62 representing my improved form of wound inner stator. Said wires on stator 115 are actually longer than shown by dimension due to the radial extension of said wires to adequately clear the rotor. The reduced length of wire in my improved stator is very beneficial as the wire is very fine due to the normally high voltage impressed on the local phase, and, therefore, a substantial reduction in length of one turn reduces the entire resistance of the winding very materially. The value of such reduced resistance will be more fully understood by reference to the vector diagram in Fig. 8, the angle Y representing substantially the phase displacement obtained by my improved form of stator, whereas, angle X represents substantially that of an externally wound stator as, for example, stator 115. The line y, representing the track, or resistive phase, or winding.

The operation of my improved relay is as follows:—Figs. 1, 2, and 3, illustrate what is known in the art as a quick-acting two-position relay. Energizing of windings on stator 62, causes rotor 68 to actuate lever 74 through the included angle H, moving from stop 74b, to stop 74a, this movement being known as picking up the relay to the front contact position, and, as said movement occurs, the cir-

cuit through contacts 10—10 will be closed and those through 11—11 will be opened, such opening and closing being more fully described in my co-pending application for Letters Patent Serial Number 65,399, filed October 28th, 1925. De-energizing of said windings will cause lever 74 to return to stop 74b, by action of counter-weight 39, said last named movement causing the circuits through contacts 10—10 to be opened, and those through contacts 11—11 to be closed, this being known as dropping away to the back-contact position.

As shown in Figs. 1, 2, and 3, lever 74 is assumed to traveling from stop 74b to stop 74a, the several views showing the relation of the moving parts with said lever equi-distant said stops.

Refer now to Figs. 9, 10, 11 and 12, illustrating the parts required to convert relay 1, into a three position normal acting device. Lever 74, link 77, lever 43, lever 37 and counter-weight 39, are omitted and the several parts illustrated in said views are substituted therefore. When windings on stator 62 are energized in a manner whereby rotor 68 revolves in the direction of arrow J, sector 83 will move in the direction of arrow M, thereby raising counter weight 91 to stop 106, and through link 111, causes contact bar 7 to move in the direction of arrow R, in this manner closing the circuits through the contacts 10—10, this being also known as the front, or clear position. De-energizing of said winding causes counterweight 91 to return to lower stop 102, in this manner returning contact bar 7, to the neutral or de-energized position, as shown in the several views. Energy to said winding in a direction opposite to that hereinbefore described will cause rotor 68 to rotate in the direction of arrow K, sector 83 moving in the direction of arrow N, and contact bar in the direction of arrow P. By this movement the circuits through contacts 11 are closed and those through 10—10 are opened, this being known as the back contact, or cancellation position.

When relay 1, is to be operated as a two position normal speed device, namely, wherein the moving parts assume only two fixed positions, the lever 37 and its counter weight 39, as well as counter weight 91 and link 89 are omitted, likewise slot 92 in link 88, for which a hole is substituted. Further, the leverage of arm 109 is substantially doubled whereby the extreme movement of counter weight 90, within the limits of its stops will cause contact bar 7, to move throughout the entire included angle S. Obviously said bar will move from full back contact position to full front contact position as the relay is energized and vice versa when said relay is de-energized.

When relay 1, is operated as a three posi-

tion device lever 37 and its counter weight 39 are also omitted.

It will be noted that by the novel arrangement of the stator 53, core 62, and rotor 68, vertical air gaps between said members are obtained, and, should dirt, or foreign matter enter therein, it will fall through to the bottom of case 44, and, by so doing, precludes any chance of rotor 68 sticking in the clear position, a very serious offense in the signalling art. It is obvious that operation of said parts in a horizontal plane will permit dirt and foreign matter to accumulate in the air gaps, and as the movement of said rotor is slow and the torque low, a very slight accumulation of said dirt or foreign matter in the air gaps, will result in said rotor sticking most probably in the clear position, as said relays are energized for the greater portion of the time.

Further, by the novel arrangement of placing windings on the inner stator, a much lesser amount of copper is required, resulting in, not only more economical construction, but also a local winding of much lower power factor whereby the efficiency of the relay is much improved, further resulting in a lower operating cost.

Further, by the novel arrangement of placing windings on the inner stator, they become invisible to an observer although the movement of aforesaid rotor is clearly visible to said observer.

Further, by the novel arrangement of placing the windings on the inner stator, a pleasing mechanical structure is obtained, good proportions and clean mechanical structure giving confidence to those who are interested in purchasing dependable relays.

Further, by the novel arrangement of an automatically controlled heating unit inside the relay case, a substantially uniform temperature is maintained therein, in this manner precluding any possibility of improper operation due to excessive lowered atmospheric temperatures outside the relay case.

Further, by the novel arrangement of an automatically controlled thermostat in one of the windings of said relay, any extraordinary condition producing a temperature inside said relay case, so low that, the latent heat from the stator windings combined with that of the automatically controlled heating units, are not sufficient to maintain adequate heat, will cause said thermostat to act to open the circuit in which it is placed, thereby calling attention to the extreme condition existing within said relay. Under ordinary operation such a condition is only established if one, or both of the heating units should burn out, whereafter no auxiliary heat could be supplied to the relay interior.

Counter-weight 117 serves to balance all parts of which contact bar 7 is composed and operating in a horizontal plane above the axis 65 on which said bar oscillates.

What I claim is:—

1. In an alternating current relay, in combination, an induction motor having a rotor, a substantially vertical shaft for said rotor, a pinion on said shaft, a gear sector meshing with said pinion and operating in a horizontal plane, a counter-weight pivoted to move in a vertical plane, and means connecting said sector and counter-weight whereby said counter-weight is raised when said rotor moves in one direction, but is not affected when said rotor moves in the opposite direction. 70

2. In an alternating current relay, in combination, an induction motor having a rotor, a substantially vertical shaft for said rotor, a pinion on said shaft, a gear sector meshing with said pinion and operating in a horizontal plane, a counter-weight pivoted to move in a vertical plane, a bell crank pivoted on a horizontal axis, a crank pin on said sector, and a connecting rod having one end receiving said pin, and a slot and pin connection between its outer end and said bell crank, whereby said counter-weight is raised when said rotor moves in one direction, but is not affected when said rotor moves in the opposite direction. 80

3. In a relay for railway use, in combination, an induction motor, a vertical shaft operated thereby, a pinion on said shaft, a horizontal gear sector pivoted to mesh with said pinion, a counter-weight pivoted to move in a vertical plane, means operatively connecting said sector and said counter-weight, and an adjustable stop for limiting movement of said counter-weight. 85

4. In a relay for railway use, in combination, an induction motor, a vertical shaft operated thereby, a pinion on said shaft, a horizontal gear sector pivoted to mesh with said pinion, a counter-weight pivoted to move in a vertical plane, means operatively connecting said sector and said counter-weight, and a stop for said counter-weight, including an adjustable threaded stud, a nut to lock said stud in adjusted position, and resilient means at the lower end of said stud positioned in the path of movement of said counter-weight. 100

Signed at New York city, in the county of New York, and State of New York, this 13th day of November, A. D. 1925.
